FINGER RING

Joseph Granat, San Francisco, Calif.

Application March 9, 1953, Serial No. 23,955

Term of patent 7 years

(Cl. D45—10)

To all whom it may concern:

Be it known that I, Joseph Granat, a citizen of the United States and a resident of San Francisco, county of San Francisco, California, have invented a new, original, and ornamental Design for a Finger Ring, of which the following is a specification, reference being had to the accompanying drawing forming a part thereof.

I claim:

The ornamental design for a finger ring, substantially as shown.
